UNITED STATES PATENT OFFICE.

CHARLES A. MAY, OF TRENTON, NEW JERSEY, ASSIGNOR TO THE MADDOCK POTTERY COMPANY, OF TRENTON, NEW JERSEY, A CORPORATION OF NEW JERSEY.

DESIGN FOR A PLATE OR SIMILAR ARTICLE.

SPECIFICATION forming part of Design No. 36,193, dated January 20, 1903.

Application filed December 10, 1902, Serial No. 134,709. Term of patent 7 years.

To all whom it may concern:

Be it known that I, CHARLES A. MAY, a citizen of the United States, residing at Trenton, in the county of Mercer and State of New Jersey, have invented a new, original, and ornamental Design for a Plate or Similar Article, of which the following is a specification, reference being had to the accompanying drawing, forming part thereof.

10 The figure is a top view of a plate bearing and incorporating my design.

The leading feature of my design consists of the ornamentation along the rim of the plate or similar article, substantially as shown 15 in the accompanying drawing.

In the drawing, A denotes the rim of the

plate or similar article, whose outer portion bears an ornamental wreath B, of thistles, their buds C, leaves D, and flowers E. An opening F is left between the ends of the 20 wreath for the insertion of a monogram.

What I claim is—

The ornamental design for a plate or similar article, substantially as shown and described.

25 In testimony whereof I affix my signature in presence of two witnesses.

CHAS. A. MAY.
